UNITED STATES PATENT OFFICE.

ARTHUR W. WILKINSON, OF EASTON, PENNSYLVANIA.

APPLYING DEVICE.

Application filed February 14, 1925. Serial No. 9,141.

My invention relates to applicators or devices for applying a substance and more particularly a fluid to a material and has for its object to provide a simple device

5 whereby a liquid may be efficiently applied in restricted quantity at will. The particular object of the invention is the provision of an applicator whereby a chemical solution having the property of eradicating certain stains and blemishes from fabrics or other materials may be manually applied in minute drops to the stain or other blemish in a manner to avoid injury to the fabric or other material. Other more specific objects 10 of the invention will appear from the description hereinafter.

In the accompanying drawing, which shows an example of the invention without defining its limits, Fig. 1 is an external view 20 of a device adapted for removing rust and other stains from fabrics; Fig. 2 is a longitudinal section on the line 2—2 of Fig. 1, and Fig. 3 is a sectional elevation showing another arrangement of the invention.

25 In its illustrated example the device comprises a container 5 provided with an air inlet or breathing aperture 6 and with a flooding aperture or water inlet 7, the two apertures being spaced from each other longitudinally of the container 5, said container being preferably constructed of a material, such as rubber or glass, which is not subject to attack by certain predetermined chemicals. The container 5 may be of any suitable shape and preferably is cylindrical in form with its one end tapering toward a point as indicated at 8; a capillary opening 9 is located at the apex of the tapering end and serves as an exit for a liquid, as will 30 appear more fully hereinafter. The other end of said container, in the illustrated example, is screw-threaded to receive a removable cap 10 which fits against a packing 11 of suitable material to withstand the action 35 of the previously mentioned chemicals; this packing 11 not only seals the container 5 in a fluid-tight manner but also protects the cap against contact with such liquid as may be contained in the container 5. A shell 12 is removably fitted upon the capped end of 40 the container 5 and is held in place thereon by friction or, if desired, said shell may be screw-threaded upon the cap 10; the container 5 may be provided with an annular bead 13 to arrest the movement of the shell 12 upon the container. In any case the de-

vice is of elongated form and is constructed so as to be capable of being easily grasped and held in the hand in the manner of a pen or pencil.

60 The illustrated example shows the device in a form particularly adapted for applying a chemical solution adapted to eradicate rust and other stains from fabrics or the like. For this purpose a suitable chemical, that is, any chemical, either in stick or crystal form, 65 having the property of converting iron rust into soluble form, such for example as a water soluble compound of fluorine having an acid reaction, is contained in the container 5, the drawings showing said chemical in the form of a stick 14 having its one end pointed as indicated at 15. When in place in the container 5, the stick 14 extends lengthwise thereof with the pointed end 15 70 projecting toward the opening 9. The diameter of the stick 14 is initially such that it is stopped by the taper of the end 8 at a distance from the opening 9 and so that said stick acts in the nature of a plunger as will 75 appear more fully hereinafter.

80 In practice the chemical or its equivalent, appropriate for the purpose for which the device is intended, that is for instance the stick 14, is placed within the container 5 85 after which the device is ready for use. Assuming now that it is desired to remove a rust stain from a handkerchief, the tapered end of the device is dipped into clear, clean water to an extent to bring the aperture 7 90 beneath the water but to maintain the aperture 6 out of the same. The device is held in this position for a short period to allow a restricted amount of water to flow through the aperture 7 into the container 5. After 95 the aforesaid restricted quantity of water has passed into the container, the apertures 6 and 7 are covered with the forefinger and the device is lifted from the water. With the forefinger still in position over the two 100 apertures, the device is now brought to a horizontal position in the hand and is gently shaken for a short period so that the water in the container will dissolve a restricted quantity of the chemical 14 contained therein. 105 With the forefinger still in place over the holes, the tapered end of the device is applied to the rust spot after which the finger is removed from the apertures 6 and 7. The dissolved chemical will now flow 110 through the opening 9 from the tip of the container on to the rust spot. The tapered

end of the device may be used to spread the chemical solution over the aforesaid rust spot and to work it into the same in order to bring about the complete removal of the rust 5 stain from the aforesaid handkerchief. In this way the small amount of solution which is required for an ordinary rust stain is applied while the handkerchief is protected against injury resulting from an overapplication of the solution and its spreading beyond the stain over the adjacent unstained parts of the handkerchief.

With the device in question, the chemical, either in crystalline or solid form, is thus 15 so packed that dipping of the device in water will cause enough water to pass into the container and into contact with the chemical to dissolve the same to a small extent and to create the small amount of solution which is required. The latter, as previously stated, is expelled in driplets through the opening 9 as wanted.

The shell 12 in addition to providing an increased axial length whereby the manipulation of the device is facilitated may be used also as a receptacle for additional chemical or for a reserve stick 14 as shown, instead of utilizing the shell 12 for containing a reserve stick 14, it may be utilized to 20 contain a chemical or combination of chemicals in the form of a liquid, crystalline mass or amorphous stick or in powdered form to be used for removing ink spots from fabrics or other materials or any other spots 25 or stains for which the chemical or combination of chemicals is particularly adapted. Or if desired the container, after having been used, may be detached from the shell

and inserted into the same in a reversed condition as shown in Fig. 3; in the latter case 40 the shell serves as a protector for the container.

It will, of course, be understood that the device may be used for other purposes than that described and illustrated. 45

Various changes in the specific form shown and described may be made within the scope of the claims without departing from the spirit of my invention. 50

I claim:

1. An applicator for an eradicating solution, comprising an elongated container provided with a breathing aperture and a water inlet adjacent said aperture and spaced therefrom longitudinally of the container, 55 said container being adapted to receive a stick of soluble chemical, one end of said container being shaped for working the solution into a fabric and being provided with a capillary outlet for said solution. 60

2. An applicator for an eradicating solution, comprising an elongated container provided with a breathing aperture and a water inlet adjacent said aperture and spaced therefrom longitudinally of the container, 65 said container being adapted to receive a stick of soluble chemical, one end of said container being shaped for working the solution into a fabric and being provided with a capillary outlet for said solution, a 70 cap for the other end of said container, and a hollow extension removably fitted upon said cap.

In testimony whereof I have hereunto set my hand.

ARTHUR W. WILKINSON.
